WINDOW ASSEMBLY

William D. Bayley, Springfield, Ohio

Application June 1, 1936, Serial No. 82,847

11 Claims. (Cl. 189—64)

This invention relates to detention window assemblies and in more particular to windows wherein detention bars are incorporated into the window structure.

5 An object of this invention is to provide interlocking muntin bars wherein the muntin bars are held in locked position by a duo-functional detention and key bar.

Another object of this invention is to provide 10 interlocking muntin bars held in fixed position by a duo-functional detention and key bar, wherein in the key bar is made of harder material than the muntin bars.

Another object of this invention is to provide 15 a detention window having a lattice work welded together functioning as a guard that is interlaced with the muntin bars.

Another object of this invention is to incorporate tool resisting detention bars fixedly attached to the window assembly.

Another object of this invention is to provide 20 a detention window assembly that is cheap, efficient, dependable and sufficiently strong for normal usage.

25 Fig. 1 is a perspective view of my preferred embodiment.

Fig. 2 is a vertical sectional view taken substantially on the line 2—2 of Fig. 1.

Fig. 3 is a horizontal sectional view taken substantially on the line 3—3 of Fig. 1.

30 Fig. 4 is a sectional view taken substantially on the line 4—4 of Fig. 1.

Fig. 5 is a detailed fragmentary view of the horizontal muntin bars shown in the above figures, Fig. 5 showing the intersecting portion of the bar.

Fig. 6 is a fragmentary view showing the interlocking portion of the vertical muntin bar.

Fig. 7 is a sectional view of another modification taken on the line 7—7 of Figs. 8 and 9.

Fig. 8 is a sectional view taken on the line 35 8—8 of Fig. 7.

Fig. 9 is another horizontal sectional view taken on the line 9—9 of Fig. 7.

40 Fig. 10 is a sectional view taken substantially on the line 10—10 of Figs. 8 and 9.

Fig. 11 is a fragmentary view of the horizontal bar shown in Fig. 7, showing the cut away portion adapted to receive the vertical bar.

50 Fig. 12 is a fragmentary view of the vertical bar shown in Figs. 8 and 9, showing a cut away portion adapted to receive the interlocking horizontal bar.

Fig. 13 is a fragmentary perspective view showing a step of assembly of the bars.

In some types of duo-functional window assemblies where the transversely arranged bars function both as detention bars and as muntin bars, difficulties have been encountered in securing the necessary cheapness of construction,

without sacrificing the appearance and the efficiency of the window assembly. This is further complicated when providing adequate protection across the more vulnerable area, that is, across the ventilating area.

In the present modification the vertical muntin bars 10 constitute eye bars having openings or eyes 12 longitudinally disposed with respect to the web of the vertical bars 10. These vertical bars 10 may be T-shaped in cross sectional area. As the side bars 14 are embedded in the masonry, these bars need not necessarily be T-bars; but may have oppositely disposed flanges 16 and 18, the former receiving the glazing 20 and the latter embedded in the masonry. The bars 14 15 may, however, be provided with eyes or openings similar to and aligned with the openings 12 in the webs of the bars 10.

The horizontal muntin bars 22 constitute the needle bars and may be T-shaped in cross section area, the stem of the T being provided with a downwardly projecting flange 24 at the end thereof, to give rigidity to the bar. These horizontal bars 22 may have the flanges cut away as shown at 28, so that as the needle bars 22 are passed through the openings 12 in the muntin bars 10 and rotated through 90°, the cut away portion 28 of the bar 22 overlaps the flange of the bar 10. Likewise, the cut away portion 26 may overlap the enlarged rib 30 of the eye bar 10.

Rectangular duo-functional key and detention bars 32 are then passed through the enlarged portion of the opening 12, so as to prevent rotation of the needle bar and hold it in position, thereby preventing the displacement of this bar. The cross sectional area of the duo-functional detention and key bars is sufficiently large to snugly fit into the portion of the openings 12 extending beyond the uncut web portion of the needle bars 22.

The key bars in the modification shown extend horizontally in close spaced relation and preferably on the under side of the muntin bar 22. The key bars 32 may be of tool resisting material so as to deter the severing of the horizontal bars, thereby functioning as detention bars. The tool resisting muntin bars 32 however, do not deter or prevent the inmates from cutting the vertical muntin bars 10.

By severing these vertical muntin bars 10 it may give the inmates a fairly good leverage to twist, bend or deflect the horizontal detention bars, even though these bars are not severed. For institutions used in confining or excluding 55 "hard boiled" criminals, or others, it may also be desirable to provide tool resisting portions aligned with and contiguous to the vertical bars.

Vertical detention bars of tool resisting material may be used in parallel width and embraced 60

by the vertical bars across the ventilating area which may include a group of spaces that are not glazed; but detention bars positioned adjacent to the webs of the muntin bars extending 5 across the glazed portions of the window obstruct the easy glazing thereof. It is preferable to find some other suitable location for the tool resistant detention bars extending across the ventilating area.

10 In the modification disclosed and best seen in Fig. 4, tool resistant rectangular detention bars 40 extend across the ventilating areas and are placed along the side of the web of the detention bars 10. The detention bars 40 prevent the easy 15 cutting of the detention bars 10 across the more vulnerable portion of the window.

A cap member 50 provided with a suitable recess is preferably used to cover the flanges of the muntin bar 10 extending across the fixed 20 spaces. These cap members prevent the sawing of the muntin bars 10; but do not obstruct the glazing of the fixed spaces, as the cap members 50 are placed on the inside of the glazing. It does, however, prevent the inmates from severing 25 the muntin bar above and below the ventilating area, as this cap member 50 is made from tool resisting material.

Member 50 is provided with extensions 51 overlying the flanges of the transversely disposed 30 muntin bars. In order to accommodate the closure frame, the extension 51 terminating at the ventilating area is provided with a lip 53 that overlaps an outwardly projecting flange 55 of the closure frame 60.

35 Suitable holes 52 extending through the flanges of the muntin bar 10 permit the pouring of fused metal so as to weld member 50 to the muntin bar. Both of the flanges are preferably provided with such holes 52, although only one has been 40 shown. Member 50 in the modification disclosed extends from one muntin bar to the adjacent muntin bar. It could, however, extend continuously along the entire face of the flanges of the muntin bar 10 from the top to the bottom of the 45 window. Likewise, it could extend across the ventilating area by providing clearance therefor or sufficiently offsetting the closure.

In the present instance the closure includes a 50 movable member not shown, pivotally attached to the frame 60 that is mounted upon a sill 64 interlocking the flange of the muntin bar bounding the bottom of the ventilating area. The closure may be any conventional type movably mounted at the bottom, at the top, at either 55 side or along the center or otherwise.

Referring to the modification disclosed in Figs. 7 to 13 inclusive, the horizontal T-bars 10 have been provided with T-shaped openings 72 terminating in an enlarged portion 74 and the 60 vertical muntin bars 76 have cut away portions 78. The T-shaped openings 72 are sufficiently large to bodily receive the needle bar 76, which is passed through the openings 72 until the cut 65 away portion 78 registers with the proper T-bar, at which time the bar 76 is bodily moved so as to position the flange 80 in alignment with the flanges 82, the flanges 82 being seated in the cut away portion 78.

70 When the needle bar 76 has been thus positioned, a duo-functional detention and key bar 84, preferably made of tool resisting material and square in cross sectional area, is passed through the openings 74 in alignment with the 75 web of the T-bar 76 so as to interlock the bars

in fixed relation with respect to each other, as shown at the extreme right of Fig. 12.

For this type of construction it is quite desirable that the maximum width of the T-bar 76 be somewhat less than the width of the web of the horizontal bar 10. As the key bars 84 are positioned along the outer edges of the webs of the T-bars 76, sufficient clearance is provided for the insertion of the glazing so that the duo-functional detention and key bars 84 may extend across both the ventilating area and the fixed glazed spaces.

In this modification it is not absolutely necessary in order to provide proper protection across the ventilating area to have the muntin bar extend continuously across both the ventilating area and the fixed glazed spaces. The muntin bars may terminate at the ventilating area. When they do, it might be desirable to provide additional protection for this more vulnerable area.

In the modification disclosed in Figs. 7 and 9, transverse detention bars 86, which may have notches in the side thereof, extend across the ventilating area and are welded to the vertical key bars 84 and to the muntin bars bounding the ventilating area. The transverse detention bars 84, which are preferably of tool-proof material, may also be used to prevent the severing of the muntin bars bounding the ventilating area and the other muntin bars disposed at right angles to the duo-functional detention and key bars 84.

In some structures the horizontal bars 86, or for that matter the vertical bars 84, may be eliminated at the fixed glazed spaces. If so, either the horizontal bars or the vertical bars or both may be provided with capping members 50, similar to those which have already been described in connection with the modification disclosed in Figs. 1 to 7 inclusive, and shown in detail in Fig. 3.

The unglazed ventilating area is preferably provided with a closure assembly only the frame 90 of which has been shown, as any suitable movable closure may be used with this frame.

The lips 53 of the cap members 50 overlap the outwardly projecting flanges 92 of the frame 90. The flange portion 92 extending along the bottom of the window interlocks or overlaps the sill member 64. Along the top of the window capping member 94 overlaps the upwardly projecting flange portion 92.

The cap members 50 and the sill 64 may be fixedly attached to the muntin bars by welding, either at the factory or on the job.

The ventilating frame may be inserted much the same as the window panes, namely by inserting the top flange under the lips 51 or the top flange under member 94 and then shoving the lower flange over the top of the sill 64.

As members 50 and capping member 94 are made from tool resisting material, these deter the severance of the adjacent portions of the muntin bars.

Although the preferred modifications of the device have been described, it will be understood that within the purview of this invention various changes may be made in the form, details, proportion and arrangement of parts which generally stated consist in a device capable of carrying out the objects set forth, in the novel parts, combination of parts and mode of operation, as disclosed and defined in the appended claims.

Having thus described my invention, I claim:

1. A detention window assembly including a plurality of transversely arranged muntin bars

dividing the window into a plurality of spaces, some of said muntin bars having eyes which receive other of said bars, duo-functional key and detention bars extending through the eyes in parallel relation to said other bars for preventing removal thereof, and detention bars extending parallel to the eye bars and in spaced relation therefrom for preventing the escape of a human body through the window assembly, said detention bars being fixedly attached to at least some of the muntin bars.

2. A detention window assembly including a plurality of transversely arranged muntin bars dividing the window into a plurality of spaces, some of which are glazed leaving at least one space vacant for ventilation, some of said bars constituting needle bars extending through eyes of the remaining bars, duo-functional detention and key bars extending through the eyes preventing the removal of the needle bars and additional bars extending across the ventilating area constituting the more vulnerable portion of the window, said additional bars being arranged between adjacent muntin bars.

25 3. A detention window assembly including a plurality of transversely arranged muntin bars dividing the window into a plurality of spaces, some of which are glazed leaving a space larger than one of the glazed spaces as a ventilating area, some of said muntin bars constituting needle bars passing through eyes in the remaining bars, said bars aligned with the ventilating opening terminating at the boundary thereof, and duo-functional key and detention bars passing 30 through the eyes to lock the needle bars in position, said duo-functional bars extending across the ventilating area to prevent escape of a human body through the window assembly.

4. A detention window assembly including a plurality of transversely arranged muntin bars dividing the window into a plurality of spaces, some of said spaces being glazed leaving a space larger than one of said glazed spaces vacant as a ventilating area, some of said muntin bars 40 constituting needle bars extending through eyes in the remaining bars, and duo-functional detention and key bars extending in parallel relation to the needle bars and extending through the eyes to lock the needle bars in position, said duo-functional bars extending across the ventilating area as detention bars and auxiliary bars extending across the ventilating area to protect the more vulnerable portion of the window, said auxiliary bars being disposed intermediate the adjacent muntin bars.

5. A detention window assembly including a plurality of transversely arranged muntin bars dividing the window into a plurality of spaces, some of said spaces being glazed leaving at least one space larger than one of said glazed spaces vacant as a ventilating area, the muntin bars aligned with the ventilating area terminating at the boundary thereof, some of said muntin bars constituting needle bars extending through eyes of the remaining bars, duo-functional detention and key bars extending in parallel relation with respect to the needle bars and extending through the eyes of the remaining bars to lock the needle bars in position, and detention means associated with the eye bars cooperating with the key bars to prevent the escape of a human being through the window.

6. A window assembly including a plurality of transversely arranged muntin bars dividing the

window into a plurality of spaces, some of said bars constituting flanged needle bars passing through eyes in the remaining bars, and key bars passing through said eyes in parallel relation to the needle bars and arranged to interlock the bars in fixed relation, the key bars cooperating with the flanges of the flanged needle bars to form putty receiving channels.

7. A window assembly including a plurality of transversely arranged muntin bars dividing the window into a plurality of spaces, some of said bars constituting needle bars passing through eyes in the remaining bars, and key bars passing through said eyes in parallel relation to the needle bars and arranged to interlock the bars in fixed relation, said key bars cooperating with the needle bars to form putty receiving seats.

8. A window assembly including a plurality of transversely arranged muntin bars dividing the window into a plurality of spaces, some of said bars constituting eye-bars having the eyes arranged in aligned relation, and supporting bars passing through the eyes in parallel relation to some of the muntin bars, each supporting bar cooperating with an adjacent parallel muntin bar 25 in forming a putty receiving seat.

9. A window assembly including a plurality of transversely arranged T-shaped muntin bars dividing the window into a plurality of spaces, some of said bars constituting needle bars passing through eyes in the remaining bars, each of the needle bars having a stem that is substantially smaller than the stems of the eye bars, the flanges of the needle bars being notched so that as the needle bars are moved laterally the 30 notches enclose the flanges of the eye bars, the openings in the eye bars adjacent the portions through which the stems of the needle bars pass being wider than the width of the stems, and key bars passed through said enlarged opening 40 after the needle bar has been moved laterally to lock the needle bar in position thereby holding the transversely disposed bars in interlocked relation.

10. A detention window assembly including a plurality of transversely arranged muntin bars dividing the window into a plurality of spaces, some of said muntin bars constituting horizontally disposed needle bars extending through eyes of the vertical bars, each of said needle bars having a flange extending downwardly from one side of the main body portion thereof, and key bars extending in parallel relation with respect to the needle bars, nestled underneath the main body portions and seated against the downwardly 50 projecting flanges so as to be partially protected from the elements by the main body portions and the flanges which form a shelter for the key bars, said key bars locking the needle bars so as to hold the needle bars and eye bars in position.

11. A window assembly including a plurality of transversely arranged muntin bars dividing the window into a plurality of spaces, some of said bars constituting T-shaped needle bars passing through eyes in the remaining bars, and key 65 bars passing through said eyes in parallel relation to the needle bars and arranged to interlock the bars in fixed relation, the key bars being disposed at the ends of the stems of the T-bars opposite the flanges, so as to have a symmetrical 70 appearance with respect to the flanges of the T-bars.
